UNITED STATES PATENT OFFICE.

GEORGE B. HAINES, OF CHICAGO, ILLINOIS.

FIRE-EXTINGUISHER AND THE LIKE.

1,335,682.

Specification of Letters Patent. Patented Mar. 30, 1920.

Application filed February 8, 1919. Serial No. 275,694.

To all whom it may concern:

Be it known that I, GEORGE B. HAINES, a citizen of the United States, residing at Chicago, in the county of Cook, and State of Illinois, have invented certain new and useful Improvements in Fire-Extinguishers and the like, of which the following is a specification.

The present invention has to do with improvements in fire extinguishers and the like of that type in which a suitable liquid or chemical carried in a tank or other container may be forcibly expelled through a nozzle so as to direct the same into the fire. Apparatus of this type operate generally on the principle of the creation of a sufficient hydrostatic pressure within the tank to expel the contents thereof with sufficient violence to cause said contents to carry over to the desired point. One method of generating this hydrostatic pressure consists in the introduction of suitable chemicals into the body of the liquid, which chemicals, by re-action either among themselves or with the liquid contained in the tank, will generate gases which will give the desired hydrostatic pressure.

When the hydrostatic pressure is to be generated by a chemical re-action, it is customary to carry one of the chemicals in a glass or other flask or bottle which may be broken at the will of the operator to permit its contents to reach the other ingredients with which the re-action is to occur. One of the objects of the present invention is to provide a greatly improved container and operating mechanism for the same and one which will be of great durability and permanence. Also in this connection to provide a construction which will be capable of standing a very heavy pressure such as will be generated and such as is desired in order to secure the proper discharge of the contents.

Other objects and uses of the invention will appear from a detailed description of the same which consists in the features of construction and combinations of parts hereinafter described and claimed.

In the drawings:

Figure 1 shows a longitudinal cross section through the central portion of an appliance embodying the features of the present invention, the same being equipped for

securing the hydrostatic pressure by chemical re-action;

Fig. 2 is a view similar to Fig. 1, with the exception that it is taken at right angles thereto;

Fig. 3 shows a vertical longitudinal section through the bottom head and the plunger and flask or bottle of the construction shown in Figs. 1 and 2, the same being on enlarged scale as compared to said figures;

Fig. 4 shows an enlarged longitudinal fragmentary section of the upper portion of the tank, having the discharge nozzle applied thereto;

Fig. 5 is a view similar to Fig. 4, with the exception that a valve has been inserted between the injector tube and nozzle for the purpose of controlling the discharge when air pressure is to be used;

Fig. 6 is a fragmentary view of the valve turned into position for charging by compressed air; and

Fig. 7 is a fragmentary view corresponding to Fig. 6, with the exception that the valve has been turned into position for discharging purposes.

Considering first the general construction shown in Figs. 1 and 2, the same includes a longitudinal cylindrical tank 12. This tank comprises a circular cylindrical body portion 13, and upper and lower heads 14 and 15, respectively. These upper and lower heads are spherical in form, so that they will most easily and perfectly resist the large pressures generated or used within the tank.

The heads 14 and 15 may be attached to the cylindrical body portion in any suitable manner, but the construction illustrated is very well adapted for resisting large pressures and also for permanence of construction. In this construction which is shown in detail in Fig. 3, the head is provided with an outwardly turned flange 16 which seats just inside of the end portion 17 of the cylindrical tank. This end portion is then folded over to provide the lap 18, thereby gripping the flange 16 solidly, making a gas and air tight construction, and also one which is able to resist abnormal internal pressures. In order to prevent a possible longitudinal displacement of the head inwardly, I provide an inwardly extending

bead 19 on the end portion of the cylindrical body, the same being immediately adjacent to the position occupied by the head and making it impossible for said head to be 5 displaced inwardly.

It will be readily appreciated that when the cylindrical body portion and heads are made of copper or other highly malleable or ductile material, an extremely tight and 10 permanent connection can be established by constructions such as that just described. In the constructions illustrated, this type of attachment is shown for both the upper and lower heads 14 and 15.

Ordinarily the apparatus is suspended in a vertical position such as that illustrated in Figs. 1 and 2. For this purpose I have shown an eye 20 connected to the cylindrical body portion by a tab 21 which may be 15 riveted thereto in the well understood manner. A handle 22 may be fastened to the body portion, preferably in its center, so that when the appliance is to be used, it may be readily manipulated by grasping this 20 handle, lifting the appliance away from the hook on which the eye has been suspended, and then directing the discharge nozzle in the proper direction with one hand. When supported by the eye 20 in this natural manner, the liquid will ordinarily stand at a level 25 such as that shown by the lines 23 in the several figures. A nozzle is provided at the upper end of the tank generally in the top head 14 through which the material is discharged. This nozzle 24 is shown in detail section in Figs. 4 and 5, and in elevation in Figs. 1 and 2. It is provided with a tapered bore 25 terminating in a discharge orifice 26. Its lower end is internally threaded, 30 so that it can be readily attached to the head or to the pipe passing therethrough.

A fitting 27 is provided for delivering the liquid through the upper head 14. This fitting comprises a stem portion 28 which extends downwardly on the interior of the tank, a nipple portion 29 which extends outwardly from the head 14, and a flange 30 which lies against the inner face of the head 14. A nut 31 is threaded down over 35 the nipple 29 so as to clamp the head 14 firmly between the nut and the flange 30, and thus secure an extremely tight connection.

Ordinarily the adjacent surfaces of the flange 30 and the nut 31 will be tinned or 40 otherwise coated with soldering material before they are secured into place on the copper head 14. After the nut has been clamped solidly into position so as to grip the head in a very firm manner, the parts 45 may be heated by a torch or otherwise, and thereupon the parts will be soldered together and provide a practically integral construction. If necessary additional solder may be introduced around the peripheries of the 50 parts.

An injector tube 32 extends down from the stem portion 28 to a point adjacent to the bottom of the tank—that is, adjacent to the bottom head 15. This tube preferably is of tapered cross section, as will be appreciated 55 from a comparison of Figs. 1 and 2, its lower end 33 being very much larger in cross section than its upper end where it passes into the stem 28. Inasmuch as the liquid enters the lower end which is of 60 large cross section, the velocity of said liquid will be increased as it rises through the tube until, when it reaches the upper end, it will have a considerable portion of its static or pressure energy converted into dynamic or 65 velocity energy preparatory to its discharge. Also the friction will be accordingly reduced. A strap 34 serves as a convenient support for holding the lower end 33 firmly against the lower portion of the tank. Ordinarily the injector tube 32 will be brazed 70 to the stem 28 of the fitting 27, so that when the fitting is subsequently heated or soldered, the tube will not separate from the stem 28.

When the appliance is to be used for the 75 generation of the hydrostatic pressure by chemical re-action, means must be provided for carrying the proper chemical within the tank and for discharging the same into the 80 contents of the tank at the proper time. I will now describe such an arrangement. The same includes a peculiarly shaped glass 85 sealed acid bottle 35 within which is carried one of the chemical constituents selected for bringing about the re-action desired for 90 the generation of the gas. The bottom head 15 is provided with a central passage through which extends a fitting 36 shown in detail in Fig. 3. Said fitting includes a stem 37, which extends to the interior of the 95 tank, a stem 38 which extends to the exterior of the tank, and a flange 39 which lies evenly against the outside face of the tank around the opening thereof. A nut 40 is threaded on to the stem 37 and against 100 the inside face of the head 15. Ordinarily the flange 39 and nut 40 will have their adjacent faces tinned or soldered before the 105 parts are set together, so that after they have been tightened up the application of 110 heat to this fitting 36 and to the copper head 115 15 will result in a soldering or brazing action, thereby uniting the fitting 36 with the head 15 in a substantially integral manner.

When the chemical bottle 35 is to be used, a basket 41 may be set up through the fitting 36 to the interior of the tank, said basket having its upper end 42 at a sufficient distance within the tank to properly accommodate the size of the bottle 35 which has been selected. This basket is provided with a 120 large number of perforations 43 through which the chemical from the bottle may be 125 discharged into the liquid contents of the 130

5 tank. The lower end of the basket 41 is outwardly flanged as at 44, said flange being adapted to seat directly against the stem 38 of the fitting 36 or a gasket 45 illustrated in Fig. 3 may be set between the parts. A cap 46 is adapted to thread over the stem 38 and close the lower end of the same. This cap is provided on its upper or inner face with a circular groove 47 shown in detail in Fig. 3, 10 which thread is provided by a pair of concentric lips 48 and 49 on the upper face of the cap. A washer 50 set between the cap and the flange 44 of the basket 41 will be very solidly gripped and held in a gas-tight manner by the cap on account of the presence of this circular groove 47 and the lips 48 and 49. In fact with this thread or arrangement, the cap will remain gas-tight for many years in succession. A pair of horns 20 51 and 52 on the cap 46 serves as a convenient means for tightening up the same, while adding materially to the appearance of the apparatus, making it unnecessary to use wrenches, etc.

25 When the hydrostatic pressure is to be generated by chemical re-action means must be provided for breaking the bottle when the operator so desires. Such means comprises a plunger 53 on which the bottle 35 rests, so that upon forcing said plunger upwardly the bottle will be crushed between the plunger and the upper end 42 of the basket. The plunger is mounted upon the upper end of a rod 54 which extends down through a stuffing box 55 in the cap 46 and has a button or handle 56 on its lower end. A stuffing box nut 57 is provided for tightening up the stuffing box in order to make it gas and liquid tight.

40 A spring 58 is located between the upper end of the bottle 35 and the upper end 42 of the basket, which spring exerts sufficient pressure on the bottle at all times to hold it solidly in position without breaking it, 45 thereby preventing any rattling or other undesired movement.

When the appliance is to be used, it is removed from the hook and the button 56 is driven forcibly against the floor or any other 50 suitable object, whereupon the bottle will be broken and the hydrostatic pressure generated and the discharge will commence at once.

When the apparatus is to be used with air pressure, it is unnecessary to provide for the bottle 35 or the plunger 53 by which it is broken. It is in like manner unnecessary to provide for the basket 41 or the spring 58.

Since the air pressure will exist within the 60 application before it is used, and probably afterward, it is necessary to provide some form of valve for controlling the discharge. This valve is shown by the fitting 63 in Figs. 5, 6, and 7. Said fitting is provided 65 with a flange 64 which seats down over the

nipple 29 previously described, and is provided with a nipple 65 onto which the nozzle 24 may be threaded. The valve fitting 63 is provided with a longitudinal bore 66 and with a nipple 67 extending at right angles thereto and provided with a bore 68. An air hose from an air supply pipe tank or pump may be threaded onto the nipple 67 when the tank is to be charged with air. A plug valve 69 having the operating handle 70 75 70 is rotatably mounted in the fitting 63, said plug valve having a transverse bore 71 and a passage at right angles thereto 72.

When the tank is to be charged with air, the plug valve is turned into the position 80 shown in Fig. 6, and when the tank has been charged, the valve may be turned into the position shown in Fig. 5, so as to shut off the interior of the tank from both the nipple 67 and nozzle 24. When the contents of the tank are to be discharged, the valve is turned into the position of Fig. 7, whereupon a straight line passage is provided through the fitting 63. I have also provided a small valve 72^a working in the nipple 67, and serving to prevent any back flow of air through said nipple.

It will be observed that when this apparatus is being used without any valve 63, as will be the case when it is being operated 95 chemically, the only area of its liquid contents exposed to the atmosphere will be the small area within the upper portion of the tube 32. Consequently, the contents of the body of the appliance cannot deteriorate by 100 exposure to the air.

In the construction of the apparatus, the fitting 27 will ordinarily be attached to the upper head 14, after which said head will be attached to the upper end of the tank 105 body. After this the fitting 36 may be attached to the lower head 15, which head may thereupon be attached to the lower end of the tank body, and thus making it possible to bring about the construction of the 110 device in the most natural and easy manner.

It is to be noted that the nipple 29 of the upper fitting 27 is bent or deflected with respect to the axis of the container, so that the nozzle 24 is directed outwardly away 115 from the axis of the container. Consequently, when the handle 22 is grasped in the natural manner for operation of the appliance, the nozzle is directed more or less in a downward direction, and, therefore, the contents can be easily directed toward the point of conflagration. It is also to be noted that since the bore 25 of the nozzle extends axially of the nozzle, it is immaterial just how far the nozzle is threaded 120 down onto the nipple 29 because the bore of the nozzle will always lie in a direction to deliver the liquid contents straight out from the appliance. Such an arrangement is to be distinguished from one in which the 125 130

bore of the nozzle does not extend directly in an axial direction, because in such case it is necessary to thread the nozzle down to a certain point in order to insure that the bore of the nozzle shall point in the proper direction.

It is also to be noted that as far as the features of construction in reference to the bottom head 15 and the fitting therein are concerned, the chamber of the container does not need to be of cylindrical form.

I claim:

- 15 1. The combination of a cylindrical casing, an upper head on the same, a fitting for said upper head comprising an integral stem on the inside of the casing, a threaded nipple extending through the head close to the side of the casing, a flange on the stem in engagement with the inside face of the head, a nut threaded on to the nipple and in engagement with the outside face of the head, a discharge nozzle threaded on to the nipple, a tubular member having its upper end connected to the stem aforesaid and its lower end relatively broad adjacent to the lower end of the casing and in close prox-
- 20
- 25

imity to the side thereof, and a closure for the lower end of the casing, substantially as described.

2. The combination of a cylindrical casing, a dish-shaped head on the upper end of the same, a fitting for said upper head comprising an integral stem on the inside of the casing and extending in a direction substantially parallel to the inner surface 35 of the casing, a nipple extending through the head in a direction perpendicular to the head at that point, a flange on the stem and in engagement with the inner surface of the head, a locking device on the nipple and 40 in engagement with the outer surface of the head, a discharge nozzle in conjunction with the nipple, a tubular member having its upper end connected to the stem and its lower end close to the lower end of the casing, the lower end of said tubular member being elliptical in cross section and having its broader surface lying close to the inner surface of the casing, and a closure for the lower end of the casing, substantially as 45 50 described.

GEORGE B. HAINES.
